UNITED STATES PATENT OFFICE.

CAMPBELL MACMILLAN, OF SCHENECTADY, NEW YORK, ASSIGNOR TO GENERAL ELECTRIC COMPANY, A CORPORATION OF NEW YORK.

ALTERNATING CURRENT DYNAMO-ELECTRIC-MACHINE WINDING.

Original No. 1,530,466, dated March 17, 1925, Serial No. 730,966, filed August 8, 1924. Application for reissue filed May 22, 1925. Serial No. 32,205.

To all whom it may concern:

Be it known that I, CAMPBELL MACMILLAN, a citizen of the United States, residing at Schenectady, in the county of Schenectady, State of New York, have invented certain new and useful Improvements in Alternating Current Dynamo-Electric-Machine Windings, of which the following is a specification.

10 My invention relates to the windings of alternating current dynamo electric machines and its object is to provide a simple and efficient winding arrangement which is substantially free from detrimental harmonics. Such a winding has a special value as a primary winding for induction motors.

15 In selecting primary induction motor windings for use in conjunction with squirrel cage secondaries, it is necessary to take certain precautions against the production of higher harmonics of flux and current which might prove detrimental in operation. The objectional operating features to be guarded against are chiefly induction 20 subsynchronous and synchronous subsynchronous speeds commonly called crawling speeds and locking at standstill. These defects are caused by higher harmonics of primary current distribution, of permeance 25 variations in the air gap, or by combinations 30 of the two in certain relationships.

The harmonics of primary current distribution, or winding harmonics, may be reduced by care in the selection of appropriate coil pitches in conjunction with the distribution constants which is determined by the number of phases and type of winding used. The permeance harmonics must be taken care of by a judicious selection of 35 slot numbers, primary and secondary. In the successful design of an induction motor other factors must also be considered with the problem of eliminating harmful harmonics. Thus, it is desirable that the winding space be completely and efficiently utilized, and that the end connections be simple and not require an excessive amount of copper. From a manufacturing standpoint, it is desirable that the coils be similar and 40 easily replaced. The present invention relates to a double layer winding in which the above-mentioned factors, going to make up a successful design, are considered together

and in which the ideal conditions are realized in a high degree. 55

The features of my invention which are believed to be novel and patentable will be pointed out in the claims appended hereto.

For a better understanding of my invention, reference is made in the following description to the accompanying drawing wherein Fig. 1 represents the primary winding of a two pole, three phase, squirrel cage induction motor built in accordance with my invention, and Fig. 2 is a vectorial 60 representation of how a detrimental winding harmonic is reduced to a harmless value by such a winding arrangement. 65

Referring to Fig. 1, I have here represented a two layer primary stator winding 70 for a two pole, three phase motor having 36 slots with two coil sides per slot, one above the other. The three phases are represented by distinguishing lines. Thus, phase A is represented by light full lines, phase B by heavy full lines and phase C by broken lines. It will be noticed that the coils are all similar and, hence, desirable 75 from a manufacturing standpoint.

Hitherto it has been universally assumed that the best results from the point of view of current distribution for any specified number of phases and slots per pole would always be obtained by placing all coils of one phase per pole in adjacent slots. The 80 truth of this assumption is evident when only the fundamental distribution of current is considered, but when harmonics are taken into consideration it may be more profitable to make a slight sacrifice in the highest value of fundamental distribution factor, in order to reduce the distribution factors of harmonics, and I have discovered that such a result can be obtained in certain cases by interchanging the positions of 85 marginal coils in adjacent phase belts without appreciably affecting the fundamental distribution and without sacrificing mechanical simplicity. Such an arrangement 90 is represented in Fig. 1.

The two pole, three phase winding of Fig. 1 is star connected, 10 being the star point. Points 11, 12, and 13 represent the line connections to the phases, A, B, and C, respectively. The connections between coils 95 of a phase belt constitute the short connec- 100

tions 14 and the slightly longer connections 15, and the connections from one pole winding to the other pole winding is represented at 16. The pitch, it will be noted, is about 61% which, in accordance with standard practice, makes the winding relatively immune from the 7th winding harmonic.

Considering one layer of this winding, it will be seen that it has the following slot arrangement 10 CAAAAABABBBBCBCCCCA per pole whereas the usual arrangement is AAAAAAABBBBBBCCCCCC. The first-mentioned arrangement having marginal coils in adjacent phase belts interchanged 15 is what I term an "interspersed" coil winding. By means of the usual vector polygon representation of distribution constants it can be shown that the particular interspersed coil arrangement shown is highly 20 advantageous from the point of view of suppressing the fifth harmonic without seriously affecting the fundamental distribution.

The vector polygon representation for 25 this particular case is shown in Fig. 2 where it is compared to that obtained by the usual winding arrangement. In the present case, we have six slots per phase belt representing 60 electrical degrees so that the vector voltage per slot must be combined at angles of 10° (electrical). The distribution factor for the usual winding would be represented by the length of the cord 20-21 in Fig. 2. By the term distribution factor I mean the 30 ratio of the vector sum to the algebraic sum of the voltages contributed by adjacent conductors in series. Expressed algebraically, this is for the usual winding:

$$40 \frac{2 \cos 5^\circ + 2 \cos 15^\circ + 2 \cos 25^\circ}{6} = .956143.$$

Now for the interspersed fundamental, the outside coil sides of a phase belt are separated from the remainder of the phase belt 45 by one slot space so that for these outside coils the voltage vector must be drawn at an angle of 20° to the adjacent voltage vector of the phase belt instead of at 10° as with the normal winding. This is represented by the dotted lines 22-23 and 24-25. The fundamental distribution factor for the interspersed arrangement is represented by the length of the cord 22-25. Expressed 50 algebraically, this is

$$55 \frac{2 \cos 5^\circ + 2 \cos 15^\circ + 2 \cos 35^\circ}{6} = .92709$$

which is only slightly less than that for the 60 normal winding.

Considering, now, the fifth harmonic, the slot intervals correspond to 50 electrical degrees, that is to say, the voltage vectors for the fifth harmonic should be drawn at 50° to each other so that the fifth harmonic distribution vector diagram per phase belt

for the normal winding would be represented by the open polygon 26, 27, 28 in Fig. 2, and the distribution factor by the length of cord 26-28. Expressed algebraically, this is:

$$2 \cos 25^\circ + 2 \cos 75^\circ + 2 \cos 125^\circ \frac{6}{6} = .19718.$$

In most cases this fifth harmonic would be harmful and cause the motor to stick at a 75 subsynchronous speed.

For the interspersed winding, the fifth harmonic voltage vector in the outside slots of the phase belt must be drawn at an angle of 100° instead of 50° to the next adjacent 80 voltage vectors of the phase belt because of the intervening slot so that the vector diagram now becomes 29-31-27-33-30 and the distribution factor equal to the length of cord 29-30. Expressed algebraically, 85 this is

$$2 \cos 25^\circ - 2 \cos 75^\circ - 2 \cos 175^\circ \frac{6}{6} = .05631.$$

Comparing these values, it is seen that the 90 fundamental distribution factor has been reduced by 3% by interspersing the coils while the fifth harmonic has been reduced by 71%. The fifth harmonic is thus reduced to a 95 value when it renders the crawling speed tendency negligible and harmless while the fundamental distribution is not appreciably decreased.

The same process of reasoning applies 100 equally well to the other layer of the double layer winding shown in Fig. 1 and the superposition of the two layers detracts nothing from the relative immunity of each layer from harmonics. Since a double layer winding is specified it is subject to changes 105 in coil pitch without disturbing the interspersing in the separate layers. Thus, a coil pitch may be selected which renders the machine relatively immune from one detrimental harmonic, for example, the seventh 110 harmonic in accordance with standard practice, and then the coils may be interspersed to render the winding relatively immune from another detrimental harmonic, for example, the fifth harmonic in accordance with 115 the present invention.

In the most usual cases the number of slots may be such as to provide no opportunity for the complete elimination of one or two harmonics by reduced pitch and interspersing, but each method may secure a substantial compromise reduction in both harmonics, and the effect of both methods, used jointly, is to multiply together the reduction factors obtained by each method 120 separately. For example, in the case cited, a coil of 61% pitch only reduces the full pitch value of the 5th harmonics to 95% and of the 7th harmonics to 27%. Interspersing, which in this case corresponds in 125 130

effect to a coil pitch reduction in each layer to 83%, reduces the full pitch values of the harmonics to 15% and 19% respectively. The combined result is a reduction of the 5th 5 harmonics to $95 \times .15 = 14.25$, and of the 7th to $27 \times .19 = 5.14$ of full pitch values. This may be accomplished without appreciably lowering the efficiency of the machine as regards 10 normal operation. Thus, in Fig. 1, it is seen that the periphery of the stator is completely utilized with no idle coils or slots, while similar form wound coils may be used without complicated or lengthy end connections.

It is not always easy to anticipate whether 15 a particular machine will be subject to a harmful harmonic or not. The present invention affords an easy way of changing connections after a machine has come to test and found to have a harmful harmonic so as 20 to reduce such harmonic to a harmless value. Thus, suppose the machine having the same pole number, pitch, etc. as represented in Fig. 1, but having the coils connected in the usual way without interspersing, comes to 25 test, and is found to have a harmful fifth harmonic. It is only necessary to change the end connections of a few coils to render the machine immune to this harmful harmonic. This is done by merely changing 30 shorter end connections like 14 to the longer end connections like 15, so as to change the connection of the coils in adjacent slots in series at the extremities of each phase belt to the interspersed arrangement illustrated.

35 While I have hereinbefore especially mentioned alternating current motors, the invention is applicable to any alternating current dynamo electric machine having a distributed double layer winding where it is desired to eliminate or reduce detrimental harmonics for any reason.

In accordance with the provisions of the 45 patent statutes, I have described the principle of operation of my invention, together with the apparatus which I now consider to represent the best embodiment thereof; but I desire to have it understood that the apparatus shown and described is only illustrative and that the invention may be carried 50 out by other arrangements.

55 What I claim as new and desire to secure by Letters Patent of the United States is:—

1. A harmonic reducing winding arrangement for alternating current dynamo electric machines comprising a slotted magnetic member having a distributed double layer alternating current winding therein, said winding being made up of similar coils with marginal coils in adjacent phase belts interchanged.

60 2. A harmonic reducing winding arrange-

ment for alternating current dynamo electric machines comprising a slotted magnetic member having a distributed double layer alternating current winding therein, said winding having a coil pitch selected so as to make the winding substantially immune from a particular winding harmonic and having marginal coils in adjacent phase belts interchanged to reduce the harmful effects 65 of another winding harmonic.

3. A harmonic reducing winding arrangement for alternating current dynamo electrical machines comprising a slotted magnetic member, a distributed double layer alternating current winding in said slots, said winding being made up of similar coils and having marginal coils of the adjacent phase belts interchanged in both layers.

4. A primary member for induction 75 motors comprising a slotted magnetic member having a distributed double layer alternating current winding therein, said winding being made up of similar coils with marginal coils in adjacent phase belts interchanged.

5. A primary member for induction 80 motors comprising a slotted magnetic member having a distributed double layer alternating current winding therein, said winding having a coil pitch selected so as to make the winding substantially immune from a particular winding harmonic and having marginal coils in adjacent phase belts interchanged to reduce the harmful effects of another winding harmonic.

6. A primary member for induction 85 motors comprising a slotted magnetic member, a distributed double layer alternating current winding in said slots, said winding being made up of similar coils and having marginal coils of adjacent phase belts interchanged in both layers.

7. A primary member for induction 90 motors comprising a slotted magnetic member, a distributed double layer alternating current winding in said slots made up of similar coils, the marginal coils of each phase belt being separated from the remainder of the phase belt by at least one slot in both 95 layers.

8. A primary member for induction 100 motors comprising a slotted magnetic member having a distributed double layer alternating current winding therein, said winding having a coil pitch selected to reduce harmful 105 harmonics and having marginal coils in adjacent phase belts of both layers interchanged to obtain a still further reduction 110 in such harmonics.

115 In witness whereof, I have hereunto set 120 my hand this 12th day of May 1925.

CAMPBELL MACMILLAN.
